(57) **CLAIM**

I claim the ornamental design for a fire resistant housing for a light fixture, as shown and described.

DESCRIPTION

FIG. 1 is a bottom perspective view of the fire resistant housing for a light fixture;

FIG. 2 is a bottom plan view thereof;

FIG. 3 is a front side view thereof;

FIG. 4 is a rear side view thereof;

FIG. 5 is a left side view thereof;

FIG. 6 is a right side view thereof;

FIG. 7 is a top plan view thereof; and,

FIG. 8 is a top perspective view thereof.
